FUR STOLE CONVERTIBLE TO A JACKET

Max Koch, New York, N. Y.

Application February 4, 1952, Serial No. 269,762

8 Claims. (Cl. 2--88)

1

The present invention relates to garments and more particularly to garments of the type ordinarily made of luxurious furs.

Generally, the present invention comprises a garment which is convertible at will, from a stole into a sleeved jacket or vice versa.

By providing a convertible garment of this character, a single garment effectively constitutes a two garment wardrobe.

An object of the invention is to provide concealed fastening means in the end or tails of the stole and in the lower edge portions of the back thereof which will permit the ends of the stole to be detachably secured within the lower edges of the rear portion to form two sleeves, thereby converting the stole into a jacket of the so-called "Bolero" style.

A further object of the invention is to provide pockets at the lower edges of the back or rear portion of the stole, within which the fastening means are disposed, these pockets being of sufficient size to receive the ends of the stole.

A further object of the invention is to provide a pocket in each end or tail of the stole, in which fastening means are disposed, and which cooperate in detachably securing the ends of the stole within the rear pockets, the pockets in the ends of the stole serving to conceal the fastening means disposed therein while the garment is being worn as a stole. While worn as a jacket, the mutually engaging pockets both cooperate to conceal the fastening means.

Other and further objects will become apparent upon reading the following specification together with the accompanying drawing forming a part thereof.

Referring to the drawing:

Fig. 1 is a perspective view showing the garment being worn as a stole.

Fig. 2 is a perspective view showing the garment being worn as a jacket.

Fig. 3 is a rear view, illustrating the location of the mutually engaging fastening means with the garment being worn as a jacket.

Fig. 4 is a plan view of the stole laid out flat, looking at the lining, the view being partly broken away.

Fig. 5 is a sectional view taken along the line 5--5 of Fig. 4, looking in the direction of the arrows.

Fig. 6 is a sectional view taken along the line 6--6 of Fig. 4, looking in the direction of the arrows.

Fig. 7 is a sectional view taken along the line 7--7 of Fig. 5, looking in the direction of the arrows.

2

Fig. 8 is a sectional view taken along the line 8--8 of Fig. 6, looking in the direction of the arrows.

Fig. 9 is a sectional view taken along the line 9--9 of Fig. 3 and showing the section of Fig. 5 in engagement with the section of Fig. 6.

Figs. 10, 11 and 12 are sectional views similar to Fig. 9, each illustrating a different modified form of the invention.

Referring to Fig. 1, the garment designated generally as 20 is of symmetrical construction. The same comprises a central back covering portion 25a from which extend shoulder covering portions 25. Extending therefrom are front free hanging portions 29a having lower ends or tails 21. The garment is shown being worn as a stole, with the front portions 29a hanging free, so that they extend downwardly as indicated. The garment 20 is provided with an upstanding collar portion 22, which is shown notched at 23 (Fig. 3) for purposes of styling and appearance. The garment 20 extends downwardly at the rear with a graceful curvature along the lowermost edge at 24 to form the back portion 25a of suitable length.

The garment 20 comprises an outer covering of fur 26. The inner surface of the fur 26 is lined with a suitable lining of fabric 27, in the usual manner.

In order to secure the garment about the shoulders of the wearer particularly when arranged as a jacket, an eye 28 is located in the collar portion 22 suitably spaced from the rear ornamental notch 23 and is removably engageable with a hook 29 located on the opposite side of collar 22 and at about the same distance from the notch 23. When eye 28 is in engagement with hook 29, the garment 20 will hang symmetrically about the shoulders of the wearer generally as shown in Fig. 2, with the collar closed. If desired, the collar may be closed when the ends are hanging free as in Fig. 1.

The end or tail portions 21 as shown in Fig. 1 are open at their lower extremities and are provided with upwardly extending internal pockets 30. The pockets 30 are shown, by way of illustration, as being open at both ends. Disposed in each of the pockets 30 is a transversely extending slide fastener 31 (Fig. 4 and Fig. 5).

Slide fastener 31 is of the usual form of construction comprising tooth elements 32 clamped to fabric 33 and secured to the fur 26 by a row of stitching 34. Reinforcement is provided by a tape 35, which is secured along the lower side thereof together with slide fastener 31, by the row of stitching 34 and along its upper edge by a further row of stitching 36. At the lower edge

of the interior of pockets 30 is a further reinforcing tape 37 which is also held at its upper edge by the row of stitching 34, and which is folded inwardly along with the fur 26 to form a finished lower edge or cuff held together by a row of stitching 38.

Disposed above the lower edge of the rear 25a of the garment and spaced at each side of the curved portion 24 are further pockets 40, each pocket being open along its lower edge. The lower edge of each pocket coincides with the lower edge of the rear portion of the garment. The pockets 40 are large enough to receive and retain the ends or tails 21 of garment 20 together with their end pockets 30.

Each of the pockets 40 (Fig. 6) comprises a fabric wall 41 adjacent to the lining 27 and secured thereto at its lower edge by a row of stitching 42. The opposite or outer side of each pocket 40 comprises a fabric wall 43 secured to fur 26 by a row of stitching 45. Two strips of fabric 46 and 47 are secured between the upper edges of the fabric walls 41 and 43 by this row of stitching 45 and the lower edges of fabric strips 46 and 47 are folded inwardly and secured together by a row of stitching 49.

Secured between strips 46 and 47 by the row of stitching 49, is the fabric portion 50 of a slide fastener designated generally as 51 which comprises teeth 52. Teeth 52 of slide fastener 51 are shaped and spaced for complementary engagement with the teeth 32 of slide fastener 31, a slide closing member 53 (Fig. 4) being provided for engaging and disengaging the teeth. A tongue and socket (not shown) provide means of conventional construction for positioning the two slide fasteners 31 and 51 for engagement or disengagement of their respective teeth by the slide closing member 53. When the slide fasteners 31 and 51 are disengaged, the slide member 53 is carried by the slide fastener 51.

Fig. 9 shows the two pockets 30 and 40 in engagement with each other being held in this position by the mutually engaging slide fasteners 31 and 51 respectively.

Fig. 10 shows an alternative form of fastening means comprising opposed rows of spaced snap fasteners 60 and 61 which are used instead of the slide fasteners 31 and 51.

Fig. 11 shows a further alternative form of fastening means comprising a row of hooks 62 engageable with eyes 63 and Fig. 12 shows a row of buttons 64 in engagement with button holes 65.

In operation, the end or tail portions 21 comprising the pockets 30 are positioned within the larger pockets 40, and the slide fasteners, or other fastening means within the pockets are brought into engagement in the usual and appropriate manner. This results in a jacket with sleeves 70, as shown in Figs. 2 and 3. To convert the garment back into a stole, the fastening means are simply unfastened, and the garment may again be worn as a stole, as shown in Fig. 1.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

I claim:

1. A garment comprising a portion to cover the back of the wearer, portions extending therefrom to cover the shoulders of the wearer, and portions extending from the shoulder portions adapted to hang down at the front of the wearer and having lower end portions, the back portion having a lower edge, pockets at the lower edge of said back portion adapted to receive the lower ends of the front portions and means to detachably fasten said ends within said pockets to form arm sleeves.
2. The combination of claim 1, said means comprising fastener means within the pocket and complementary fastener means in said ends, and pocket means on said ends to conceal the fastener means thereon.
3. The combination of claim 2, said garment having an outer fur layer and an inner lining and said pockets being located between the fur layer and lining.
4. An elongated stole type garment comprising tail portions having pockets therein and having further pockets disposed intermediate the tail portions said further pockets being adapted to receive said tail portions, fastening means disposed in said pockets of said tail portions, and further fastening means disposed in said intermediate pockets and engageable at will with said fastening means disposed in said pockets of said tail portions.
5. An elongated stole type garment having end portions and comprising an outer fur covering and a lining; a pocket disposed at each end of the garment intermediate said outer covering and said lining; fastening means disposed in each of said pockets; two further pockets disposed intermediate said ends and intermediate said outer covering and said lining and adapted to receive said end portions; and further fastening means disposed in said last named pockets and detachably engageable at will with said first named fastening means.
6. A garment as in claim 5 in which all of said fastening means are disposed in a normally concealed position within said pockets.
7. A garment as in claim 5 in which said further pockets disposed intermediate said ends, each has an opening adjacent to the same edge of said garment.
8. A garment as in claim 5 in which each of the fastening means is secured to a strip of fabric secured within one of the pockets.

MAX KOCH.
